[57] **CLAIM**

The ornamental design for mixed terminal electrical connector plug, as shown and described.

DESCRIPTION

FIG. 1 is a perspective view of the mixed terminal electrical connector plug showing our new design;

FIG. 2 is a front elevation thereof;

FIG. 3 is an end elevation thereof;

FIG. 4 is a rear elevation thereof;

FIG. 5 is a top plan view thereof; and

FIG. 6 is a bottom plan view thereof.
